UNITED STATES PATENT OFFICE.

STANLEY FORSYTH BARKER, OF CHICAGO, ILLINOIS.

TEMPERATURE-INDICATING MECHANISM.

Application filed September 20, 1921. Serial No. 501,938.

The present invention relates to signal devices and has to do particularly with temperature actuated or thermal alarms.

Well knowing the mental association with changes in temperature of the rise and fall of the fluid within the capillary stem of a thermometer, my primary object has been to devise a mechanism in which an increase of temperature is indicated by a rise in a visual signal, and a reduction in temperature by a lowering of such signal.

Secondarily, it is an object to provide a mechanism, accurate, rapid, and certain of operation, in which the signal is moved against a fixed and constant resistance. Additionally, it is an object of this invention to provide a particularly effective alarm, magnifying the expansion and contraction of the actuating member in a device of simple structure, of inexpensive manufacture, and in which the parts are so constructed and arranged that disorder is almost impossible.

These and such other objects as may hereinafter appear are attained by the novel construction, combination and arrangement of parts to be hereinafter specifically described and claimed. Reference will now be had to the accompanying drawing forming a part of this specification, wherein:

Figure 1 is a fragmentary front view of the invention;

Figure 2 is a vertical section of one embodiment of my invention;

Figure 3 is a vertical section of the same embodiment of my invention at right angles to that of Figure 2;

Figure 4 is a fragmentary vertical section of a second embodiment of the invention;

Figure 5 is a similar view of a third embodiment of the invention; and

Figure 6 is a detail (in perspective) clarifying structural features of the embodiment disclosed in Figure 5.

Like reference characters are used upon the drawings and throughout the description of the invention which follows to indicate similar parts.

As shown, the device comprises, broadly, a thermal member, a signal member actuated by the thermal member, and a housing member for said thermal and signal members. The invention resides in the form and operation of the several members referred to, in the agency employed for communicating variations in temperature to the signal

member and in the correlation of each member with the other members.

Referring now to Figures 1, 2, and 3, it will be noted that the housing comprises an upper section or signal casing 10, cylindrical in form, having a boss 11 at its lowermost point, and a lower section or stem 12 for enclosing a thermal member 13. Intermediate the casing 10 and the thermal member 13 the stem 12 is provided with a rectangular passage, the purpose of which will be later described.

The walls of the stem 12 which surround and completely enclose the thermal member 13, are thinned out or of reduced thickness to admit of rapid conduction of heat or cold to the thermal member 13. This latter comprises laminations of metals having unequal expansion by increment of heat, bound one to another in the ordinary manner, such member 13 being substantially U shaped and having its end pivotally connected to a system of levers 14, ordinarily designated lazy-tongs, passing upwardly through the stem 12 into the casing 10, where the upper extremities are joined to the shutter or indicator 15 by a pair of inwardly pointed short bars, designated 14'.

Said indicator 15, having parallel sides and a rectangular configuration, is provided with an extension 15' upon its lower side to facilitate connection with the bars 14'. Reciprocating freely upon the parallel tracks 16, the supports 16' of which are fastened in casing 10, the indicator 15 responds instantly to any impulse communicated to the lazy-tongs 14 by the thermal member 13, which latter is arranged to bend inwardly at its ends upon the application of heat thereto. The units of the lazy-tongs 14 are guided against displacement and held in vertical alignment by the parallel walls of the apertured stem 12, thus preventing lost motion without undue friction.

While both ends of the casing 10 may be provided with flat glass plates, such as 10', one side thereof may be provided with a meniscus lens, 10^a for enhancing the visuality of the indicator 15. The latter is preferably of a bright color while the glass end 10', except its central portion 17, is colored black or some dull color, to accelerate visibility of the signal.

Indicia of any desired type, as, for example, the words "Average", "Danger", and

"Freezing", shown in Figure 1, may be arranged to provide, by reference to the position of indicator 15 with respect thereto, for instantly understanding thermometric conditions existing about and in the vicinity of thermal member 13.

If it is desirable or preferable to avoid painting or marking the glass end 10', an apertured disk, upon which the necessary indicia are stamped, printed or painted may be employed, such disk being adjacent to the interior surface of the glass end 10' and secured in the casing 10 by the means holding said end against displacement therefrom.

15 The description of the embodiment of my invention disclosed hereinbefore given clearly shows the manner of its operation. The temperature about stem 12 is conducted to thermal member 13 within said stem. Heat 20 causes said member 13 to bend inwardly, and cold reverses the direction of its distortion.

The impulses from the movements of said member 13 are received by and communicated, in a magnified form, through the lazy-tongs to the indicator 15 which rises with an increase and falls with a reduction of temperature. A thermometric or other scale could be substituted for the indicia here disclosed. At all times the weight of the indicator 15 and the lazy-tongs 14 is borne directly by the thermal unit 13, irrespective of the position of the indicator 15 or lazy-tongs 14.

In Figure 4, and in Figures 5 and 6, two additional embodiments of my invention are illustrated. In the first of these figures, it is showed that I employ a thermal element 13^a comprising two U shaped members riveted together to form a W shaped element. The outer end of one of said U shaped members is rigidly affixed to the housing 12^a. The outer end of the other of said members actuates an indicator 15^a through a lever 18, fulcrumed at 18'. The longer arm of said lever 18 is pivoted to a short bar 19 similarly attached to a bar or stem 14^a depending vertically from indicator 15^a while the shorter arm of said lever 18 is actuated by a bar 20, pivotally connected at one end to said short lever arm and at its other end to the movable end of element 13^a.

By this arrangement of parts, the indicator 15^a is displaced downwardly and upwardly concurrently with every impulse of the movable end of 13^a, while the magnitude of the displacement of said indicator 15^a is to that of the thermal element 13^a, a number of times greater.

In Figure 5 a compound thermal element 60 13^b similar to or identical with element 13^a of Figure 4 is shown. Instead of securing said element to the housing, stem or casing for the thermal element, I provide a plate 21 and supporting disk 22 connected in the manner showed in Figure 6.

Supporting disk 22, while substantially circular in shape, is cut or made with flattened portion. As shown in Figure 6, the material of the disk is cut parallel and perpendicularly to its shortest dimension to provide a tongue 23, bent vertically downward and upon which plate 21 is secured by rivets or spot welding. The boss 11^b is internally threaded to receive a threaded tubular stem not shown which completely surrounds but does not engage element 13^b or plate 21 and as it is screwed home forces the disk 22 against a shoulder at the termination of the rectangular passageway through the boss 11^b, said boss being apertured in the same manner as boss 11 depicted in Figures 1, 2 and 3. Except for the portion bent downwardly to form tongue 23, the disk 22 is of the same diameter as the threaded portion of boss 11^b. Upon the lower surface of said shoulder are depending vertical pins or studs 24 adapted to be inserted through apertures 25 in disk 22 positioned to correspond with said pins or studs 24 whereby to facilitate alignment of plate 21 with indicator 15^b and to prevent rotary displacement of said plate 21 and the parts supported thereby.

The thermal element 13^b may be secured rigidly, at one end, to plate 21 by a pin or other fastening means, or a stud may be arranged upon said plate 21 to allow for slight oscillations of the thermal element, the connection between the plate 21 and the thermal element 13^b, being indicated by the ordinal 26. At its other end, said thermal element 13^b is pivoted to the short arm of a bell crank lever 27 fulcrumed on a stud 28 carried by plate 21. Depending from and affixed to the indicator 15^b to admit of oscillatory motion, is a relatively long bar 29. The lowermost extremity of said bar 29, is pivoted to one end of a lever 30 oscillating upon a stud fastened to plate 21 at a point more elevated than the lowermost extension of bar 29. Intermediate the lever 30 and the extremity of the longer arm of bell crank lever 27 is a link 31 having pivotal connections at its opposite ends with lever 30 and lever 27. The position of the pivot between link 31 and lever 30 upon the latter, is a factor in determining the magnitude of the displacement of indicator 15^b as will be readily appreciated.

Every distortion inward or outward of the thermal member 13^b is thus communicated to the indicator 15^b, the displacement of the latter having a linear magnitude several times in excess of that of the former. The embodiment of my invention disclosed in Figures 5 and 6 has an added advantage of allowing assembly of all small parts before insertion into the housing for the device, also increased accessibility to the parts.

Particular attention is drawn to the arrangement of the several lever systems which

I employ and which provide enlarged displacements of the indicator member directly proportional to the distortion of the thermal member but which may also be modified 5 to give slight displacement to the indicator between the extremes of a normal condition and accelerated movement, in either direction, upon the approach of a dangerous high or low degree of temperature.

10 While I have illustrated several forms of my invention, it is manifest that I have not illustrated every means by which the invention can be carried out. It is, therefore, not my intention to be limited to the disclosures 15 illustrated but to claim all modifications, changes, and alterations of and to the means depicted which come within the spirit of the invention.

What I claim is new and desire to procure by Letters Patent of the United States 20 is:

1. In a temperature indicating mechanism, a thermostatic element, a housing therefor, a vertically reciprocal signal in said housing, 25 and a plurality of levers intermediate said signal and said element whereby the movement of said element is translated into a vertical displacement of said signal.

2. In a temperature indicating mechanism, 30 a thermostatic element, a housing therefor, a vertically reciprocal signal in said housing, and connecting means intermediate said signal and element to accentuate the translation of said signal responsive to the movement of 35 said thermostatic element.

3. A temperature indicating device including a housing, a signal, a thermostatic element, and connecting members therebetween, said connecting members comprising a lever

having one end pivoted to said housing, means 40 for actuating the signal in a linear path at the other end of said lever, and means connecting said lever to the thermostatic element and engaging said lever at a point intermediate its ends. 45

4. A signal device comprising a housing, vertically reciprocating signal means within said housing, a plate member disposed in said housing, a horizontally expansible thermostatic element having one end movably connected to said plate, and a plurality of levers 50 associated with said plate and pivotally secured to the free end of said thermostatic element and to said signal means.

5. In a temperature indicating device, a 55 reciprocating shutter, a casing therefor, an L-shaped plate carrying a plurality of levers for increasing linear displacement, a thermostatic element secured to said plate and to the least displaced of said levers, a housing for 60 said L-shaped plate and said thermostatic element, and a link intermediate the most displaced of said levers and said reciprocating shutter, said housing and casing when connected engaging said L-shaped plate there- 65 between to maintain the device in operable position.

6. In a temperature indicating mechanism, a thermostatic element, a housing therefor, a vertically reciprocal signal in said housing, and connecting means intermediate said signal and said thermostatic element 70 whereby the movement of said element is translated into a vertical displacement of said signal. 75

In testimony whereof I affix my signature.

STANLEY FORSYTH BARKER.
